23 Sheets-Sheet 2

This technical drawing illustrates a complex mechanical assembly, possibly a cylinder or piston rod mechanism. The drawing is a line drawing with various components labeled with numbers. The components include:

- Base plate: 60, 61, 62, 63, 64, 65, 66, 67, 68, 69, 70, 71, 72, 73.
- Shafts: 144, 145, 146, 147, 148, 149, 150, 151, 152, 153, 154, 155, 156, 157, 158, 159, 160, 161, 162, 163, 164, 165.
- Shaft supports: 86, 87, 88, 89, 90, 91, 92, 93, 94, 95, 96, 97, 98, 99, 101, 102, 103, 104, 105, 106, 107, 108, 109, 110, 111, 112.
- Shaft sleeves: 141, 142, 143, 144, 145, 146, 147, 148, 149, 150, 151, 152, 153, 154, 155, 156, 157, 158, 159, 160, 161, 162, 163, 164, 165.
- Shaft washers: 106, 107, 108, 109, 110, 111, 112.
- Shaft keys: 103, 104, 105, 106, 107, 108, 109, 110, 111, 112.
- Shaft bearings: 141, 142, 143, 144, 145, 146, 147, 148, 149, 150, 151, 152, 153, 154, 155, 156, 157, 158, 159, 160, 161, 162, 163, 164, 165.

 The drawing uses various line weights and hatching to differentiate between different materials and parts of the assembly. The numbers are placed near the corresponding parts, often with leader lines.

MAKING AND HANDLING LATH OR THE LIKE

William M. Ries, Wheeling, W. Va., assignor to Wheeling Steel Corporation, Wheeling, W. Va.

Continuation of application Ser. No. 439,985, June 29, 1954. This application Mar. 17, 1959, Ser. No. 800,012

14 Claims. (Cl. 29—417)

This invention relates to making and handling lath or the like. It has to do with improved methods of making and handling lath or the like, and for purposes of explanation and illustration I shall describe the invention in connection with the making and handling of expanded lath. In some of its features the invention is limited to the making and handling of expanded lath but in other of its features it is not so limited and is applicable to other types of lath and to similar materials. This application is a continuation of my copending application Serial No. 439,985, filed June 29, 1954, now abandoned.

Since the invention is probably at the present time best adapted to be employed in the field of expanded metal lath the invention will be described with that field as a background although it is to be understood that the invention is not so limited. Expanded lath, while normally made out of metal, may today and in the future be made out of other material having appropriate characteristics, as, for example, certain synthetic plastics. Consequently, the term "expanded lath" as used herein contemplates lath expanded out of any suitable metal or non-metallic material.

The commercial way of making expanded metal lath at the present time, except for the plant employing my present invention, is to first provide metal sheets of proper characteristics and dimensions and then pass the sheets separately one after the other through rotary slitting and expanding apparatus. The sheets of expanded metal lath thus produced are coated with paint or other coating material and then are stacked and bundled by hand. The operation is inefficient of time and high in cost, particularly labor cost.

It has heretofore been proposed by certain patentees to form expanded metal lath continuously by feeding a coil of strip through slitting and expanding apparatus and shearing into sheets on the fly the lath thus continuously produced. However, no such method of producing expanded metal lath has proved commercially feasible, probably primarily because the lath is produced so fast that it cannot adequately be taken care of after the shearing operation without disproportionate labor cost.

I have devised a procedure whereby expanded metal lath may be made continuously and sheared into sheets on the fly and the sheets piled or stacked, bundled and subjected to after-treatments such as coating and drying wholly automatically and with no labor except machine supervision. I thus greatly reduce the cost of the lath. At the same time I produce a superior unprecedentedly uniform product and an improved bundle of sheets of lath or the like product entirely mechanically.

In the description to follow I shall refer to the blank used for producing the lath as a coil of steel strip. Conceivably a blank in other than coil form could be used but from the standpoint of economy the starting blank will normally be a coil. I feed the coiled strip continuously through slitting and expanding apparatus. The slitting and expanding apparatus per se may be conven-

2

tional. A continuous length of expanded metal lath issues from the expander. I shear the advancing lath on the fly. The lath is produced at a speed which may be of the order of 500 feet per minute.

5 I provide for delivering the advancing sheets of expanded metal lath one after the other to a receiving station and thence to a piling station where they are formed into a pile. Preferably the sheets are delivered to the receiving station in the same general direction as the direction in which the expanded metal lath issues from the expander so that the momentum of the material at least assists to a material extent in carrying it through to that station.

15 The coil of strip which forms the blank from which the expanded metal lath is made may be mounted upon a payoff reel with its axis horizontal and the strip may enter the rotary slitter not only moving in a generally horizontal direction but also oriented in a generally horizontal plane. The type of expander which I prefer to use does not expand the metal in the plane of the strip but at a substantial angle to that plane. Consequently, when the strip enters the slitter oriented in a horizontal plane the expanded metal lath is delivered from the expander in a plane inclined at a steep angle to the horizontal. When the expanded metal lath is thus delivered from the expander I prefer to pass it through guiding means which turns it gradually from a position oriented at a steep angle to the horizontal into a substantially horizontal plane. When the lath has been thus turned 20 into a substantially horizontal plane I shear it on the fly into sheets of lath which continue their movement in a substantially horizontal plane and in the same direction to the receiving station.

25 I can materially shorten the apparatus by eliminating 30 the guide for turning the lath from inclined to horizontal orientation by a novel procedure of feeding the blank to the slitter and arrangement of the slitter and expander. Instead of arranging the payoff reel carrying the coil of 35 steel strip which is the blank for forming the lath with its axis horizontal as above described I incline the axis of the payoff reel and coil at the same angle to the horizontal as the angle to the horizontal at which the lath is discharged from the expander in the procedure above described but inclined in the opposite direction. I also incline the slitter and expander relatively to the conventional orientation 40 thereof so that the blank fed thereto at a steep angle to the horizontal as above described is received in the slitter in normal fashion and is there slitted and passes to the expander also in normal fashion, the result, however, being that the lath issues from the expander in a horizontal plane instead of in a plane at a steep angle to the horizontal. This makes possible the elimination of the 45 guide for turning the lath to the horizontal, resulting in materially shortening the apparatus and reducing its cost. 50 Also the lath is not subjected to possible torsional stresses 55 and there is less danger of stoppages due to improper tracking of the lath.

When the lath is sheared into sheets the sheets follow one another without substantial change in direction to the receiving station. I preferably interpose between the shear and the receiving station a speed-up conveyor which 60 delivers each sheet from the shear at a speed somewhat higher than the speed at which the lath is delivered from the expander, thus providing spaces between the advancing sheets. Thus there is a short time interval between the time when a sheet comes to rest at the receiving station and the time when the leading end of the succeeding sheet enters the receiving station. That time interval aids materially in proper piling and handling of the sheets in the piling station and subsequently.

65 I preferably provide for receiving the sheets one by one, stopping and momentarily supporting each sheet in

predetermined position directly above the place where the pile is to be formed and then releasing the sheet and allowing it to gravitate to the pile. I provide means for receiving each sheet and supporting the sheet, preferably adjacent the sides edges of the sheet, and means for rendering the supporting means inoperative by withdrawing the same outwardly, thereby releasing the sheet and allowing it to drop. As soon as the sheet drops onto the pile the supporting means return to operative position to receive the next sheet. The supporting means may be moved to inoperative position by control means actuated by the sheet itself as it approaches the position in which it is stopped at the receiving station. I provide a somewhat resiliently mounted bumper positioned in the path of the leading edges of the sheets as they move to the receiving station to stop the sheets one after the other.

I provide for automatically forming stacks or piles each of a predetermined number of sheets and for fastening together the sheets of each such stack or pile to form a bundle. I provide control mechanism which is sensitive to the number of sheets which are released to gravitate to the pile effective when the pile consists of a predetermined number of sheets to transfer the pile from the piling station to a bundling station. For purposes of illustration it may be considered that each bundle is to consist of ten sheets. As the tenth sheet of a pile is released and falls onto the pile the pile of ten sheets moves from the piling station to the bundling station and provision is made for receiving at the piling station the first sheet of the next pile without interrupting or slowing down the delivery of sheets one after the other from the shear to the receiving station. I also preferably provide a visible counter so that the machine operator may know at any time how many sheets are in a pile being formed.

I find it desirable to position the bundling station directly beneath the piling station so that each pile of ten sheets transferred from the piling station to the bundling station moves directly downwardly from the former to the latter. I find it desirable to provide two alternately operable supporting means for supporting a pile of sheets and lowering the pile when completed from the piling station to the bundling station.

At the bundling station I preferably pass fastening means, such as wires, through openings in the sheets and fasten together the ends of the fastening means about portions of the pile to fasten the sheets of the pile together to form a bundle. Any desired number of fastening means may be utilized in the formation of each bundle. I prefer to provide three fastening means at each side edge of the bundle or a total of six fastening means per bundle. When the fastening means are wires it is convenient to accomplish the fastening function by twisting the ends of the wires together.

Since the openings in the sheets being bundled may not be, and generally are not, in exact vertical alignment I find it desirable to laterally support the flexible fastening means, such as wires, when passing them through the openings in the sheets. The lateral support thus afforded the wires enables the wires to pass through the openings in the sheets without difficulty. The sheets may be very slightly shifted or very slightly deformed adjacent the openings through which the wires are passed to permit passage of the wires each in a substantially straight line through the openings of the sheets.

I prefer to utilize generally tubular means for laterally supporting the wires as they are introduced through the openings in the sheets. I provide tubes having eccentrically pointed upper ends arranged generally vertically adjacent the side edges of the pile and means for projecting the tubes upwardly through the openings in the piled up sheets. The tubes may be made of material of adequate structural strength such as steel. As each tube moves through the pile, if it is not in exact alignment with an opening in each sheet of the pile it may slightly shift the sheet or slightly deform the material of the

sheet in forcing its way through. I find it desirable to rotate the tubes as they are advanced upwardly through the piled up sheets. As each tube rotates its eccentrically pointed upper end moves in a circle, enabling it to find the openings in the sheets as the rotating tube advances upwardly therethrough.

When each tube has passed through openings of the piled up sheets a wire is advanced through the tube. In this way the wire itself encounters no resistance from the sheets. I find it desirable to thus pass through the sheets the leading ends of wires delivered from coils. Each tube is retracted after serving its purpose of guiding the wire through the openings of the piled up sheets. The retraction of each tube may commence as soon as the wire therein has advanced far enough to insure that it will pass through all of the sheets of the pile. A part of the advancing movement of each wire may be simultaneous with a part of the retracting movement of the corresponding tube.

When each tube has been retracted so as to be clear of the pile the wire may be sheared and the ends of each wire may be brought together and twisted together about a portion of the pile. This may be effected by a retractable yoke for each wire, the portions of the wire above and below the pile engaging the yoke and the yoke being shifted outwardly beyond the edge of the pile and then turned to twist the wire ends together. The yoke may have an opening in each arm and the wire may pass through those openings.

As soon as the sheets of each pile have been fastened together in a bundle as above described the bundle is preferably advanced endwise out of the bundling station generally in the same direction as the direction of movement of sheets to the pile. The bundles thus delivered from the bundling station are successively dipped in coating material and dried, after which they are delivered to a packaging station where a predetermined number of bundles, for example fifty, are bound together into a package.

I find it desirable in moving the bundles through the coating and drying apparatus to arrange them with their long dimensions transverse of the direction of movement. Consequently, I preferably turn each bundle generally horizontally through an angle of 90° after its delivery from the bundling station and before coating. This may be accomplished by a turntable. The bundles are delivered successively from the turntable in the same general direction of advance as before but with their long dimensions transverse of the direction of advance. The bundles are successively lowered into a tank of coating material such as paint, spelter or bituminous or other coating material after which they are elevated out of the coating material and allowed to drain. The bundles are then successively moved through a drying station and are finally delivered to the packaging station.

All of the operations above described from the uncoiling of the strip as it passes to the slitting and expanding apparatus to the delivery of the coated and dried bundles at the packaging station are performed continuously and automatically without any labor other than machine supervision.

Other details, objects and advantages of the invention will become apparent as the following description of certain present preferred methods of practicing the same proceeds.

In the accompanying drawings I have illustrated certain present preferred methods of practicing the same in which

Figure 1A is a side elevational view of part of a continuous lath line showing the payoff reel with a coil of steel strip mounted on it, the slitting apparatus, the expanding apparatus, the roller leveler and guide means for guiding the expanded lath back to a horizontal plane;

Figure 31 is a transverse sectional view taken along line XXXI—XXXI of Figure 28 showing the turntable cam means; and

Figures 32A, 32B, and 32C are wiring diagrams of the continuous lath line.

Referring to the drawings, I have shown a continuous lath line (Figures 1A and 1B) having a payoff reel 1 on which a coil of steel strip 2 is placed. Strip unwound from the coil follows a path 3, indicated by chain line, through a rotary slitter 4, and expander 5 which expands the strip into expanded lath and a roller leveler 6. From the roller leveler the strip is led by a guide 8 to a set of pinch rolls 9 and a flying shear 10. At the flying shear the strip is cut into sheets and fed by the speed-up conveyor 11 to a bundler 12. In the description to follow I shall for simplicity sometimes use the term "bundler" to comprehend the sheet receiving and piling apparatus as well as the bundling apparatus. Successive sheets are fastened in the bundler into bundles of expanded lath and delivered to a turntable 13 from which the bundle is drawn into a painter 14, of which only a portion of shown in the drawings. In the modified form of continuous lath line (Figures 3A and 3B), like parts are

65 identified by like numbers with the addition of a prime. A coil of strip 2' is placed on a payoff reel 1'. The strip is fed into a rotary slitter 4' in a plane which is at an angle with the horizontal. From the rotary slitter, the strip is fed to an expander 5' and expanded to expanded lath. The angle with the horizontal at which the strip is fed into the slitter is equal to the angle between the plane of strip entering the expander and the plane of lath leaving the expander. Thus, in the modified form of 70 continuous lath line, the roller leveler 6' handles lath

75 continuous lath line, the roller leveler 6' handles lath

which is in the horizontal plane. The need for a guide to return the strip of lath is dispensed with and the strip is fed from the roller leveler directly to the pinch rolls 9' and the flying shear 10'. In all other respects, the operation of the modified lath line is identical with that shown in Figures 1A and 1B.

For convenience, the detailed description of the continuous lath line will be divided into subdivisions corresponding to various portions of the line. The entry end of the line preceding the bundler, the bundler, the fastening apparatus, the turntable, and the automatic control system will each be separately described.

The entry end of the line

The payoff reel 1 upon which the coil is placed is rotatably mounted, allowing the strip to be drawn into the rotary slitter. The payoff reel is provided with a brake 7 (Figure 2) to provide a drag on the payoff reel and prevent the inertia of the coil from unwinding more strip than is taken by the rotary slitter should the continuous lath line be stopped or slowed down. In passing through the rotary slitter cuts are made in the strip, and it is then expanded into expanded lath in the expander. It is passed through the roller leveler to remove any tendency to coil or hump. These units are old and well-known in the art (see, for example, Cross Patent No. 2,106,967) and will not be further described here. When the strip of expanded lath leaves the expander, it is at an angle to the plane of the strip entering the rotary slitter. Where the strip is fed from the payoff reel in a horizontal plane, the expanded lath will leave the expander at an angle to the horizontal. To return the lath to the horizontal plane for convenience of handling, it is fed into a guide 8 comprising an open framework which constrains the edges of the strip. The framework gradually assumes the horizontal plane. This results in the expanded lath being in the horizontal plane as it enters between the pinch rolls 9. Passing beyond the pinch rolls the lath is cut into sheets of convenient length by a flying shear 10.

The rotary slitter, the expander, the roller leveler, the pinch rolls and the flying shear are all driven from one motor (not shown in the drawings). It drives shafts 15 and 16 (Figure 2) through appropriate drive means causing rotation of the two rolls in the rotary slitter and driving the expander rolls. It similarly drives the input shaft of variable speed drive 19. The output of variable speed drive 19 drives the roller leveler through a spur gearing and the input shaft of variable speed drive 20. The output shaft of variable speed drive 20 drives shaft 21 which drives the flying shear. An extension of the input shaft of variable speed drive 20 drives a shaft similar to and behind shaft 21 driving the pinch rolls 9.

The speed-up conveyor 11 comprises a belt 11a (Figure 4A) mounted over rollers 22 and 23 which are journaled in frame 24. Motor 25 (Figure 4A) mounted on frame 24 drives roller 23 through a coupling 26, a gear box 27, and endless chain 28 which is mounted on gear box sprocket 29 and roller sprocket 30. Motor 25 drives the upper surface of the speedup belt in a direction moving from the flying shear to the bundler, and at a higher rate of speed than the speed of the strip through the part of the continuous lath line preceding the speed-up conveyor belt.

The bundler

Reference will be made generally now to Figures 4A, 4B, 5, 6, 7, 8 and 9. Upon a base 31 of the bundler is erected a framework 32. Guides 33 affixed to the framework are adapted to guide sheets delivered by the speed-up conveyor to a receiving station. The receiving station comprises a plurality of arms 34 and 35 to which a plurality of angles 34a and 35a are attached. Sheets delivered from the speed-up conveyor are delivered above and between the arms against a stop 36 (Figure 6) resiliently mounted on framework 32. Arms 34 and 35

are keyed to shafts 37 and 38 which are journaled for rotation in cross members 39, 40 and 41 of framework 32. Keyed to shaft 37 are cranks 44 and 45 (Figure 8); similarly keyed to shaft 38 are cranks 42 and 43. Linked

5 to crank 44 is an extension member 46 to which a double-acting air cylinder 47 is rigidly attached. A piston, operating in cylinder 47, mounted on piston rod 48 is linked to crank 42. Air may be supplied to the cylinder through hoses (not shown in the drawings) to forcibly drive the piston to an extended or retracted position. A link member 49, connected to cranks 43 and 45, causes any movement of the arms to be practically symmetrical with respect to the bundler frame. When the piston is moved from its retracted position, which is shown in 10 the drawings, to its extended position, the piston will move relative to the framework 32 a distance equal to one-half of its stroke. The cylinder will move in an opposite direction a distance equal to one-half of the stroke of the piston. The consequent rotation of shafts 20 37 and 38 will be of equal angularity, but of opposite direction. When the piston is in its fully extended position, the bearing surfaces 50 and 51 of the angles 34a and 35a will be withdrawn from beneath the sheet. The edges of the angles 34a and 35a nearest to the speed-up 25 conveyor have offsets 52 (Figure 5) which serve to correct misalignment of any sheet and guide it between the arms.

Suspended intermediate the speed-up conveyor 11 and the stop 36 from a beam 54 affixed to cross members 40 30 and 41 is an electric switch 53. Switch 53 is operated when a sheet of lath passes beneath roller 55 (Figure 6) raising it. The switch is affixed to beam 54 by clamps 56 engaging flanges 57 on beam 54. The clamps are 35 slideable along the flanges so that the position of the switch may be adjusted along the length of the beam.

A motor 58 (Figure 4A) drives pinion 59 (Figure 7) through gear box 60. The pinion drives gear 61 keyed to a camshaft 62 having a plurality of cams 63, 64, 65, 66, 67, 68, 69, 70, 71, 72 and 73 keyed thereto. The 40 pinion, gear and cams have been omitted from Figure 4A for clarity. Referring particularly to Figures 7, 11 and 12, cam 67 has associated with it a follower comprising a roller 74. Crank 75 comprises two identical flat plates spaced apart and rotatably mounted on a fixed shaft 76. Roller 74 is journaled at one extremity of crank 75 between the two plates. A link 77 is pinned at one of its ends to the other extremity of crank 75 and is pinned at its other end to a rod 78 mounted in a sleeve 79. Pinned to the other end of rod 78 is a link 80. Pinned above and below link 80 are two flat bars 81 which are likewise pinned above and below cranks 82, 83 and 84. At the ends of bars 81 away from link 80 a block 85 is pinned between the bars. Block 85 has 45 screwed into it a rod 86 projecting through a segment 87 of a cylinder set in the base and through a spring 88. The spring 88 is held compressed between the segment and nuts 89 threaded onto the end of the rod 86.

Splined shafts 90, 91 and 92 are slidably and rotatably fixed in brackets 93 which are affixed to the base 31 of the bundler. Cranks 82, 83 and 84 have splined holes which surround and mesh with the splined sections of splined shafts 90, 91 and 92. Mounted on the top of splined shafts 90, 91 and 92 are supports numbered 60 respectively 94, 95 and 96. Supports 95 and 96 are sectors of a circle to give greater bearing area beneath the sheets of expanded lath which they support. The supporting area of support 94 is reduced because of clearance limitations with framework 32. Rotation of cam-shaft 62 will cause rotation of cam 67. As the high point of the cam comes in contact with cam follower 74 the follower will be depressed causing crank 75 to pull link 77 away from sleeve 79. This will cause link 80, flat bars 81 and end block 85 to be pulled away from the spring. This in turn will cause rotation of shafts 90, 91 and 92 rotating supports 94, 95 and 96 from an op- 65 70 75

erative to an inoperative position. A portion of rod 86 will be pulled through the segment 87 further compressing spring 88.

A second set of supports 97, 98 and 99 (Figure 7) are mounted upon splined shafts 100, 101, and 102. These are shown in the drawings in an inoperative position. They are rotated between operative and inoperative position by a linkage similar to that used in rotating splined shafts 90, 91 and 92. This linkage is controlled by crank 103 (Figure 11) and spring 104. Crank 103, similar to crank 75, is operated by a cam 64 which is keyed to crankshaft 62. Cams 65 and 66 have been omitted from Figure 11 for clarity. A corresponding set of supports 105, 106 and 107 is similarly mounted and is operated in like manner by spring 111 and cam 72, whose profile and angular position on camshaft 62 is the same as that of cam 67. Referring to Figure 7, supports 94, 95 and 96, 105, 106 and 107 are in operative position to receive each sheet of expanded lath released from the arms 34 and 35 and comprise a piling station. Supports 108, 109 and 110 correspond in operations to supports 97, 98 and 99. They are shown in the drawings in inoperative position. Supports 108, 109 and 110 are operated by spring 112 and cam 69 whose profile and angular position on camshaft 62 are identical with those of cam 64.

Cam 66 (Figures 7 and 10) has associated with it a follower comprising a roller 113. Crank 114 comprises two identical flat plates which are spaced apart and have roller 113 journaled between them. The crank is rotatably mounted on fixed shaft 76. Pinned to the other end of crank 114 is a link 116 which connects through a series of flat bars 117 similar to those already described to a spring 118 (Figure 8) which is in compression. Cranks 119 and 120 respectively are rotatably mounted on shafts 121 and 122 fixed to the base of the bundler. Slotted trunnion blocks 123 and 124 are fixed to the other extremities of cranks 119 and 120 respectively. Splined shafts 90 and 91 project through the slots of trunnion blocks 123 and 124 respectively, and are restrained from vertical movement within the slots by shoulders and lock-nuts on the shafts. A similar crank, which is not shown in the drawings, is attached to the lower end of splined shaft 92. Rotation of camshaft 62 will cause the low portion of cam 66 to come into contact with roller 113. Spring 118 will pull on the linkage moving it toward the spring. This will cause rotation of cranks 119 and 120 about fixed shafts 121 and 122. It will likewise cause rotation of the similar crank beneath splined shaft 92. This will result in the splined shafts 90, 91 and 92. This will result in the splined shafts 90, 91 and 92 moving downwardly in the brackets 93 to a lower position. This will result in lowering supports 94, 95 and 96. Supports 105, 106 and 107 which are mounted and operated by a similar system of splined shafts, cranks and links have their elevation controlled by a spring 125 and cam 71. The profile and angular position of cam 71 on camshaft 62 are identical with that of cam 66. When cams 66 and 71 have rotated until the associated cam followers are riding on that portion of the cams designated on cam 66 by number 126, supports 94, 95, 96, 105, 106 and 107 have moved to a lower level in the bundler and comprise a bundling station. Additional lowering of elevation for purposes of withdrawal of the supports occurs when surface 127 of cam 66 and a corresponding portion of cam 71 are next to the associated followers. Elevation of supports 97, 98 and 99 is controlled by a linkage similar to that just described which is operated by cam 65 and a spring 128 (Figure 8). In similar manner the elevation of supports 108, 109 and 110 are controlled by a spring 129 and cam 70 whose profile and position on camshaft 62 are identical with those of cam 65.

Associated with cam 68 is a cam follower comprising a roller 130 (Figure 15). Crank 131 is comprised of two identical flat plates which are spaced apart and have

roller 130 journaled between them. The crank is rotatably mounted on fixed shaft 76. Pinned to the other extremity of crank 131 is a link 132. The other end of the link is pinned between two flat bars 133. Cranks 134 and 135 (Figures 4A and 4B) are keyed respectively to shafts 136 and 137 which are rotatably mounted in framework 32 of the bundler. A plurality of cranks 139 are keyed to shaft 136; and a plurality of cranks 140 are keyed to shaft 137.

10 A frame 138 is pinned to the ends of cranks 139 and 140. A plurality of upright supports 141 project above frame 138. Rotation of camshaft 62 from the position shown in Figure 15 will cause the high point of cam 68 to rotate adjacent follower 130. This will cause crank 131 to rotate about shaft 76 pulling on link 132. This in turn will cause rotation of shafts 136 and 137 which will elevate frame 138. When frame 138 is in its lowermost position the top supports 141 will be beneath a chain conveyor comprising chains 142. Elevation of frame 138 will raise the upper surface of supports 141 above the chain conveyor.

Cam 63 (Figure 13) has associated with it a cam follower comprising a roller 143. Crank 144 is mounted for rotation on fixed shaft 76 and comprises two identical flat plates spaced apart. Roller 143 is journaled between the plates. Crank 144 has a link 145 pinned to its other extremity. Pinned to link 145 is a rod 146 slidably mounted in sleeve 147. Attached to the other end of rod 146 is a link 148. Pinned above and below link 148 are flat bars 149 which are similarly pinned above and below block 150 (Figure 7). A rod 151 extends from block 150, projects through a cylindrical segment 152 and through the center of a spring 153. Nuts 154 threaded on the end of rod 151 allow the degree of compression of spring 153 to be adjusted. Pinned between flat bars 149 are cranks 155, 156 and 157 (Figures 7 and 14) which are rotatably mounted on fixed shafts 158, 159 and 160 respectively. Attached to the other extremities of cranks 155, 156 and 157 are links 161 which are in turn connected to the fastening apparatus which will be described below. Rotation of cam 63 from the position shown in Figure 13 will bring a high point on the cam next to roller 143. This will cause rotation of crank 144 and will pull link 145, rod 146, link 148 and flat bars 149 in the direction of camshaft against spring 153. This will cause rotation of cranks 155, 156 and 157 about fixed shafts 158, 159 and 160 moving the links 161 and the associated fastening apparatus toward the center line of the bundler. When the cam has been rotated so that a low spot on the cam is next to the roller, spring 153, which is in compression, will exert force to return the linkage and cranks to the position shown in the drawings and move the fastening apparatus away from the center line of the bundler. Cranks 162, 163 and 164 have a function similar to that of cranks 155, 156 and 157. Their operation is controlled through a similar linkage by cam 73 and spring 165. Cam 73 has an identical profile with that of cam 63 and has the same angular position on the camshaft 62.

60 A pinion 60a (Figure 4A), driven from gear box 60, drives gear 166 upon which a cam 167 is mounted. Gear 166 makes one revolution for each one-half revolution of camshaft 62. Cam 167 operates electric switches 168 and 169 when it passes by the switch arms. Cam 167 is positioned so that it will have just operated switch 168 at the time the cams on camshaft 62 are in the positions shown in the drawings.

70 A chain conveyor comprises three endless chains 142 which revolve around cogs 170 and 171 mounted on shafts 172 (Figure 15) and 173 (Figure 8) respectively. Shaft 172 is mounted in pillow blocks 174 which are slidably mounted on framework 32. Slack in the chains may be adjusted by changing the position of nuts 175 on rods 176, thus changing the minimum distance between shafts 172 and 173. Shaft 173 is driven by motor 178

through gear box 178a. Attached to the chains 142 are dogs 177 (Figure 24) which serve to push the rear edge of each bundle of expanded lath deposited on chains 142. Fitted on shaft 173 is a pinion 179 driving a gear 180. The gear ratio is such that gear 180 makes one revolution during the time that the chains move the distance between two successive sets of dogs. A cam 181 which is attached to gear 180 will operate an electric switch 182 which is mounted on the frame work supporting shaft 173 by contact with the switch lever. The chains 142 are guided by T-sections 183 (Figures 8 and 9) which are supported on angles 184 which in turn are supported from the base.

Guides 32a (Figure 8) are affixed to framework 32 to keep each sheet centered when arms 34 and 35 are opened. These insure that when the sheets are piled their edges will form an even edge to the pile.

The fastening apparatus

The fastening apparatus comprises six units, three on each side of the bundler, designated generally 185. Referring generally to Figures 16 through 23, one of the units will be described. A bracket 186 is mounted upon the base 31 of the bundler. Flanges 187 of the fastening unit are slidably clamped between the bracket and clamps 188. Links 161 which have heretofore been described are attached to the lower portion of the case of the fastening unit and move it along the bracket, inwardly or outwardly from the center line of the bundler, according to the position of the cams 63 and 73. From each fastening unit a support 189 projects on which a drive motor 190 (Figure 9) is mounted. On the shaft of motor 190 is a coupling 191 which drives an input shaft 192 of the fastening unit. On one end of the casing 193 of the wiring unit an extension 194 is bolted. An end bell 195 is fastened to the extension by bolts 196. The input shaft 192 is journaled in bearings 197 and 198 (Figure 17) which are mounted in the end bell. A pinion 199 is formed on the end of input shaft 192 as an integral part of the shaft (Figure 20). Mounted within extension 194 is a roller bearing 200 (Figure 17). Mounted within the roller bearing concentrically are a spider 201 and camshaft 202 which is engaged to the spider by a key 203. A roller bearing 204 mounted in the casing supports the other end of camshaft 202.

Mounted on the end of camshaft 202 nearest motor 190 is a roller bearing 205 and mounted within end bell 196 is a roller bearing 206. A planet gear carrier comprises spider 207 which is mounted on roller bearing 205, spider 208 mounted on roller bearing 206 and shafts 209, 210 and 211 (Figures 20 and 21) extending therebetween. An internal gear 212 (Figure 20) is fixed within end bell 195 by bolts 213. Keyed to bushings on shafts 209, 210 and 211, and meshing with pinion 199 and internal gear 212, are planet gears numbered 214, 215 and 216 respectively. The bushings are rotatable on shafts 209, 210 and 211. Bolted to the end of spider 201 by bolts 217 is an internal gear 218 (Figure 21). Roller bearings 219 and 220 are mounted in the hollow center of camshaft 202 at opposite ends. A spindle drive shaft 221 is journaled in the bearings. A pinion 222 is formed on the end of spindle drive shaft 221 as an integral part of the shaft (Figure 21). Keyed to bushings on shafts 209, 210 and 211 and meshing with internal gear 218 and pinion 222 are planet gears respectively numbered 223, 224 and 225. Planet gear 223 is attached to planet gear 214 (Figure 20) by bolts 226. In like manner planet gears 215 and 224 are attached by bolts 227 and planet gears 216 and 225 are attached by bolts 228.

Around the circumference of the portion of camshaft 202 (Figure 17) having the greatest diameter two cam tracks are cut. A slotted member 233 is mounted in the casing. On one end a roller 230 is rotatably mounted and is fitted within one of the two cam tracks cut in the greatest diameter of camshaft 202. A shear knife 234 is mounted within the slot at the other end of member 233

from roller 230. Member 231 is slidably mounted in the slot in member 233. It has a roller 229 rotatably mounted on one end and fitted within the other cam track, and a shear knife 232, which operates in conjunction with knife 234, mounted on its other end. When the rollers 229 and 230 are in the portions of the cam tracks marked 235 and 238, as shown in Figure 17, the shear knives 232 and 234 are in their extreme closed position. When the camshaft 202 has made one-half of a revolution, the rollers 229 and 230 will be in the portion of the cam tracks marked 236 and 237, and the shear knives 232 and 234 will be in their extreme open position. One revolution of camshaft 202 is effective to open and to close shear knives 232 and 234.

Fixed to one end of spindle drive shaft 221 is a bevel gear 239. A vertical shaft 240 upon which roller bearings 241 are mounted is fixed in the fastening end of the casing. Mounted upon the roller bearings is a compound gear 242 having bevel teeth 243 and spur teeth 244. The bevel teeth mesh with the teeth of bevel gear 239.

Concentric with camshaft 202 is a member 245 keyed to camshaft 202 by a key 246. Gear teeth are cut around part of the circumference of portion 245a of member 245 (Figure 23). Mounted in the lower portion of the casing are roller bearings 247 and 248 in which a countershaft 249 is journaled. Countershaft 249 has an intermittent pinion 250 cut in its end which meshes intermittently with the teeth cut in portion 245a of member 245.

On the other end of countershaft 249 a pinion 251 is formed as an integral part of the countershaft. An idler pinion 252 is mounted in the casing and meshes with pinion 251. A bushing 253 (Figure 22) and a roller bearing 254 are mounted in a lower portion of the casing.

A shaft 255 having pinion 256 keyed to it is journaled in the bearing and bushing. Pinion 256 meshes with idler pinion 252. On the other end of shaft 255 is fastened a grooved fastening wire feed role 257 having a groove 258 cut around its circumference. A shaft 259 is mounted parallel to shaft 255 in roller bearing 260 and bushing

261. A spring 265 which is compressed between the casing and bushing 261 normally serves to maintain the flat fastening wire feed roll 262 in contact with the grooved fastening wire feed roll 257. On one end of shaft 259 a flat fastening wire feed roll 262 is mounted.

On the other end of shaft 259 a pinion 259a is fastened which meshes with pinion 256. An extension of shaft 259 rotates in a bushing 263 mounted in a lever 264. Lever 264 has an offset 266 (Figure 18) which is recessed in the casing. Depressing the tip of lever 264 will cause

it to rotate about the offset forcing shaft 259 and bushing 261 outwardly against spring 265 and moving the flat fastening wire feed roll 262 out of contact with the grooved fastening wire feed roll 257.

Mounted on the end of countershaft 249 is a spider 267 (Figure 17) on which a slide block 268 is rotatably mounted by pin 269. A carriage 270 is free to move in a vertical direction between the casing of the fastening unit and guides 271 (Figure 18). Mounted in the upper and lower ends of carriage 270 are roller bearings 272 and

273 (Figure 17) in which a spindle 274 is journaled. The spindle has splined teeth 275 which mesh with the spur teeth 244 of compound gear 242. A groove 276 cut transverse the direction of movement of carriage 270 accommodates slide block 268. Rotation of the countershaft 249 and slide block 268 will cause carriage 270 to move up and down with simple harmonic motion. Carriage 270 is shown in its lowermost position in Figure 17. It is shown in its highest position in Figure 18.

A hollow sleeve 277 mounted in the lower portion of the casing (Figure 17) leads to a point adjacent the two fastening wire feed rolls. Wire for fastening the bundles is supplied from reels of wire (not shown in the drawings) which may be conveniently located near the lath line. The wire is conducted from the reels to a point

70

75

60

65

70

75

near hollow sleeves 277 through conduits 379 (Figure 9). An electric switch 380 is mounted on each conduit to indicate whether or not there is fastening wire feeding through the conduit.

Another hollow sleeve 278 leads from a point adjacent the fastening wire feed rolls into a hole 279 bored through the center of spindle 274. Hollow sleeve 278 is fixed to the casing and is a sliding fit within spindle 274. A pointed tubular member 280 is affixed to the upper end of spindle 274. The hole in tubular member 280 coincides with the center of rotation of spindle 274. The point 281 of tubular member 280 is off-center and will describe a circle when spindle 274 is rotated.

A shaft 282 is fixed in the upper portion of the casing of the fastening unit and has a gear member 282a rotatably mounted on it. An intermittent pinion 283 and a pinion 284 are formed as integral parts of the gear member 282a. The intermittent pinion 283 meshes with the intermittent teeth on portion 245a (Figure 23) of member 245. A carriage 285 is slidably mounted on the upper portion of the casing. This has roller bearings 286 and 287 mounted on it in which a yoke shaft 288 is journaled. Fixed to one end of the yoke shaft is a yoke 289 through whose arms holes 290 are provided. On the other end of yoke shaft 288, meshing with pinion 284, an elongated pinion 291 is formed as an integral part of yoke shaft 288. Concentrically mounted on camshaft 202 and keyed to it is a cam 292. This has a groove cut around its circumference which tracks from one end of the cam to the other. Its extreme positions are indicated by numbers 293 and 294. A roller 295 rotatably mounted on carriage 285, fits into the groove cut in cam 292.

A pin 296 is mounted in the casing on top of the fastening unit and has a clamp 297 pivotally mounted on it. The clamp has a recess 298 cut in its clamping end to accommodate the yoke 289 and tubular member 280 when they are in their extended positions. Two springs 299 and 300 (Figure 19) are mounted in the casing and are in compression between the casing and nuts on the ends of rods 301 and 302. The other ends of the rods are pierced and have protruding through them a pin 303 which projects through clamp 297 on the opposite side of pin 296 from recess 298. The springs operate to urge the clamp to its open position as shown in Figure 17. Member 245 has a cam 304 at one end. A follower comprising roller 305 is mounted in the end of push rod 306. The other end of the push rod rests against bearing plate 307 recessed in clamp 297. When the low portion of cam 304 is next to roller 305, the clamp 297 will be in its extreme open position, as shown in Figure 17. When the high portion of cam 304 is next to roller 305, the clamp 297 will be in its closed position, as shown in Figure 16. A rod 308 is threaded into one end of clamp 297 and may be locked in position by nut 309. This contacts operating pin 310 of switch 311 when clamp 297 is in the open position and causes operation of switch 311.

The turntable

The turntable which is shown generally in Figures 25 through 31 is mounted on a base 312. Projecting upwardly from the base is a collar 313 (Figure 28) in which a spindle 314 is slidably and rotatably mounted. An electric motor 315 (Figure 26) drives the input shaft 316 of a gear box 317 through a flexible coupling 318. A pinion shaft 319 (Figure 30), which is journaled in the turntable base in roller bearings 320 and 321, is driven through coupling 322 by the output shaft 323 of gear box 317. Pinions 324 and 325 are formed on pinion shaft 319 as an integral part thereof. A countershaft 326 (Figure 31) is mounted in the turntable base and has a collar 327 mounted concentrically about it on roller bearings 328 and 329. Fastened to collar 327 are a cam 330 and a gear 331 which meshes with pinion 324. Countershaft 326 has a second collar 333 concentrically mounted on roller bearings 334 and 335. Fastened to

collar 333 are a cam 336 and a gear 337 which meshes with pinion 325. The gear ratio between pinion 324 and gear 331 is twice the gear ratio between pinion 325 and gear 337 so that gear 337 makes one revolution for each one-half revolution of gear 331. Formed on the end of pinion shaft 319 is a pinion 338 (Figure 25) driving gears 339 and 340 which are rotatably mounted on stub shafts fixed in the base 312. The ratio between pinion 338 and gear 339 and between pinion 338 and gear 340 is the same as the ratio between pinion 325 and gear 337. Gears 339 and 340 make one revolution for each revolution of gear 337. Mounted on gear 339 is a cam 341 which operates lever 342 of electric switch 343. Similarly mounted on gear 340 is a cam 344 which operates lever 345 of switch 346.

A cam lever 347 (Figure 28) is rotatably mounted on shaft 348, which is mounted in the base 312. It has a follower comprising a roller 349 which rides against the surface of cam 336. On the other end of cam lever 347 are two rollers 350 which are in contact with the lower end of spindle 314.

Surrounding cam 330 is a follower comprising two side pieces 351 and 352 (Figure 26) and a spacer 353 placed between the sidepieces 351 and 352. At the other end from spacer 353 a rack 354, having gear teeth cut along one side, is mounted between the sidepieces. The teeth cut in rack 354 mesh with splined teeth 360 cut in spindle 314. Rollers 355 and 356 are mounted between sidepieces 351 and 352 and are in contact with the surface of cam 330. The cam follower is limited to straight line movement by guides 357 and 358 (Figure 30). The guides are fitted with bearing pieces 359 between which the sidepieces 351 and 352 are slidably mounted.

Operation of electric motor 315 will drive pinion shaft 319 causing pinion 324 to rotate gear 331. Collar 327 and cam 330 will rotate with gear 331. When cam 330 has made one-half of a revolution from the position shown in Figure 28, which will be in the clockwise direction, the cam follower will have moved to the extreme opposite position.

Movement of the cam follower and rack 354 through their full distance will cause the spindle 314 to make one-quarter of a revolution.

Similarly, operation of electric motor 315 will cause rotation of cam 336. Figure 28 shows roller 349 against the lowest part of cam 336. Rotation of cam 336 will likewise be in a clockwise direction (viewing Figure 28) and will cause roller 349 to ride first on a partially elevated portion 361 of cam 336 and then on a fully elevated portion 362 of cam 336, raising spindle 314 corresponding distances. Considering that cam 336 rotates twice as fast as cam 330, it will be clear from an inspection of Figure 28 that not until cam 336 has rotated so that roller 349 is next to the intermediate portion 361 of the cam 336 will there be any movement of the follower of cam 330. The turntable will then rotate one-quarter revolution before cam 336 raises spindle 314 to a higher level. Spindle 314 carries on its upper portion a frame 363 and the turntable surface 364 which is mounted in part on frame 363 and in part on the top of spindle 314 (Figure 29).

Mounted on frame 363 are a plurality of inverted cups 365 from which rods 366 depend. A spring 367 is compressed upon each rod between a nut 368 and a cup 369. The cups 369 are mounted in a frame 370 to which guides 371 are affixed. The compression of the springs is sufficient to keep frame 370 in contact with frame 363 when the turntable is in the position shown in Figure 28. When roller 349 is riding against the partially elevated portion 361 of cam 336 the frame 363 and turntable surface 364 will be partially elevated. The springs 367 will continue to maintain frame 370 and guides 371 in the same position relative to frame 363. The turntable surface and guides will be in the position shown in dotted lines in Figure 25 and indicated generally by figure 372. When spindle 314 is raised further, retainer 373 (Figure

29), which is attached to frame 370, will meet boss 374 on collar 313 and be restrained from further upward movement. Cam 336 will continue to lift spindle 314. Frame 363, turntable surface 364, cups 365, rods 366 and nuts 368 will move with it. Frame 370, cups 369 and guides 371 will be held in position by boss 374. This will result in compression of springs 367. When roller 349 is next to the high portion of cam 336 the turntable surface and guides will be in the position shown in dotted lines on Figure 25 and indicated generally by figure 375. At this time turntable surface 364 will be above guides 371.

When the turntable is raised to its fully elevated position, a bundle on the turntable will be just beneath arms 376 (Figure 1B) extending out of the painter. Dogs 377 will project from the arms behind and below the bundle. Mechanism within the painter will draw the arms into the painter, sliding the bundle of path off the turntable and into the painter. Recesses 378 (Figure 25) in the turntable surface 364 accommodate the dogs, which project below the turntable surface.

The automatic control system

The continuous lath line is operated automatically by an electric control system which is shown diagrammatically in Figures 32A, 32B and 32C. Power is supplied to the system through line wires 381 and 382 (Figure 32A). A manually operated master switch 383 connects wires 384 and 385 to the line. Pressing push button 386, which is normally open, will complete a circuit from wire 384 through wire 387, push button 386, wire 388, the coil of relay 389 and wire 390 to wire 385. Operation of relay 389 will close switches 391, 392 and 393. When switch 391 closes it will complete a holding circuit from wire 384 through push button 394, which is normally closed, wire 395, switch 391, wire 388, the coil of relay 389 and wire 390 to wire 385. When switches 392 and 393 are closed they will connect wires 384 and 385 with wires 396 and 397 respectively. Thus, closing switches 383, 392 and 393 will connect wires 396 and 397 to the power line. A switch 398 is responsive to the line pressure of a coolant which is pumped over the cutting surfaces of the rotary slitter. When full pressure is being delivered by the pump, switch 398 will close. Reference has previously been made to a switch 380 which is located on each conduit 379 (Figure 9) to indicate whether or not there is fastening wire feeding through the conduit. The switches are designated individually in Figure 32A as 380a, 380b, 380c, 380d, 380e, and 380f. When there is wire in any conduit, the switch for that conduit will be closed. When the end of a reel of wire passes through the conduit beyond the switch, the switch will open. Pressure operated switch 398, the coil of relay 399 and the six fastening wire switches 380a, 380b, 380c, 380d, 380e, 380f are all connected in series between wires 396 and 397. When switches 398, 380a, 380b, 380c, 380d, 380e, and 380f are closed, relay 399 will be energized and will close switches 400 and 401. When switch 401 is closed it completes a control circuit from the main drive motor controller 402. Controller 402 is of conventional design and is used to control the speed and operation of the main drive motor driving the rotary slitter, expander, pinch rolls and flying shear. Controller 402 will not permit the motor to run unless switch 401 is closed. When switches 400 and 403 are closed they will complete a circuit from wire 396 through motor 25 (Figure 4A) which drives the speed-up conveyor. Switch 403 is mounted on the brake of the main drive motor and will close when the brake is off and the motor running. Should the main drive motor be stopped for any reason, switch 403 will open.

A timer 404 is connected between wires 396 and 397. When a sheet of expanded lath is delivered to the bundler it will close switch 53 (Figures 6 and 32A), completing

a circuit through timer 404. After a predetermined lapse of time from the closing of switch 53, timer 404 energizes timer 405 which is connected across the line between wires 396 and 397. Timer 405 momentarily completes a circuit through the coil of relay 406 and energizes timer 407. When relay 406 is energized it closes switch 408 completing a circuit from wire 396 through coil 409 of a double-acting pneumatic valve 410 and switch 408 to wire 397. When coil 409 is energized valve 410 operates to supply compressed air delivered from an air compressor through pipe 411 to pipe 412. Pipe 412 is connected to cylinder 47 to extend piston 48. Simultaneously valve 410 allows air in the other end of cylinder 47, which is connected to pipe 413, to exhaust through pipe 414. After a predetermined time from the moment when timer 407 is energized it will momentarily complete a circuit through coil of relay 415. When relay 415 is energized it will close switches 416 and 417. When switch 416 is closed it will momentarily complete a circuit from wire 396 through coil 418 of the double-acting pneumatic valve 410 and switch 416 to wire 397. When coil 418 is energized, it will connect pipe 411, through which compressed air is supplied, to pipe 413 causing piston 48 to retract into cylinder 47. Simultaneously it will connect pipe 412 from the other side of cylinder 47 to exhaust pipe 414. When switch 417 is closed it will complete a circuit between wires 419 and 420.

Wires 419 and 420 connect to a counter 421 (Figure 32B) which is connected between wires 396 and 397. Each time switch 417 is closed it completes a circuit in the counter. When switch 417 has been closed ten times, the counter momentarily operates switch 422 completing a circuit from wire 396 through the coil of relay 423 to wire 397. The counter will at the same time reset itself so that after switch 417 has been closed ten more times, the counter will again momentarily close switch 422. When relay 423 is energized it will close switch 424. Closing switch 424 will complete a circuit from wire 396 through the coil of relay 425 to wire 397. When relay 425 is energized it will close switches 426 and 427. Closing switch 426 will complete a circuit from wire 396 through wire 428, wire 429 and motor 58 (Figures 4A and 32B) to wire 397. Closing switch 427 will complete a circuit from wire 396 through the coil of relay 425, wire 431, switch 427 and wire 432 to switch 433. Switch 433 is normally closed and is opened only when relay 434 is energized. From switch 433 wire 435 leads through switch 169 (Figures 4A and 32B). Switch 169 normally completes a circuit from wire 435 to wire 397. When relay 434 has not been energized, and, in consequence, switch 433 is closed, and switch 169 is in the normal position, operation of relay 425 will complete a holding circuit from wire 396 through the coil of relay 425, wire 431, switch 427, wire 432, switch 433, wire 435 and switch 169 to wire 397. This will serve to hold relay 425 energized. When cam 167 (Figure 4A) strikes the switch lever of switch 169 it will cause switch 169 momentarily to connect wire 436 to wire 397. At the same time, the circuit between wires 435 and 397 will be broken. This will complete a circuit from wire 396 through the coil of relay 437, wire 436 and switch 169 to wire 397. This will cause relay 437 to operate and close switch 438. A timer 439 is connected across wires 396 and 397 by wires 440 and 441. When switch 438 is closed, timer 439 will be made operative. It will complete and hold for a predetermined length of time a circuit from wire 396 through the coil of relay 442 and wire 443 to the timer, thence through wire 441 to wire 397. When the coil of relay 442 is energized, the relay will close switch 444 completing a circuit from wire 396 through the coil of relay 445 and switch 444 to wire 397.

When the coil of relay 445 is energized the relay will operate and close switches 446, 447, 448, 449, 450 and

451. Closing switch 446 will complete a circuit from wire 396 through the coil of relay 452 to wire 397 causing the relay to operate. In like manner, switches 447, 448, 449, 450 and 451 will energize the coils of and operate relays 453, 454, 455, 456 and 457. Operation of relay 452 will close switches 458 and 460 and will open switch 459. Similarly, operation of relay 453 will close switches 461 and 463, and will open switch 462; operation of relay 454 will close switches 464 and 466, and will open switch 465; operation of relay 455 will close switches 467, 469 and 470, and will open switch 468; operation of relay 456 will close switches 471 and 473, and will open switch 472; and operation of relay 457 will close switches 474, 476 and 477, and will open switch 475.

One of the relays 452 through 457 is associated with each of the fastening units. The relays control the circuits for each of the motors 190 (Figure 9) driving one of the fastening units. On the wiring diagram these motors are designated individually as 190a, 190b, 190c, 190d, 190e and 190f. When the relays operate, the motors 190a, 190b, 190c, 190d, 190e and 190f will be connected across wires 396 and 397 by switches 460, 463, 466, 469, 473 and 476 respectively. When the motor 190 on each fastening unit has driven the fastening unit sufficiently far to move clamp 297 from the open position (Figure 17) the switch 311 on that fastening unit will close. Timer 439 will hold relay 442 energized a sufficient length of time for the motors 190 to cause closing of the switches 311 before switches 446, 447, 448, 449, 450 and 451 again open. These switches are designated individually on the wiring diagram as 311a, 311b, 311c, 311d, 311e and 311f. When switches 311a and 458 are closed they complete a holding circuit from wire 396 through switch 311a, wire 478, switch 458, wire 479 and the coil of relay 452 to wire 397. In like manner circuits will be completed through the coils of the other relays by switches 311b and 461, switches 311c and 464, switches 311d and 467, switches 311e and 471 and switches 311f and 474. When relays 455 and 457 are energized a circuit will be completed from wire 397 through wire 480, switch 477, wire 481, switch 470, wire 482 and the coil of relay 434 to wire 397. When relay 434 is energized it will open switch 433 and close switches 483 and 484.

Switch 168 (Figures 4A and 32B) normally connects wire 396 to wire 485. When relay 434 is energized and switch 484 closes, a holding circuit will be completed from wire 396 through switch 168, wire 485, switch 484, wire 486 and the coil of relay 434 to wire 397.

As each of the fastening units completes its cycle, the clamp 297 (Figure 17) mounted thereon will return to the open position, opening the switches 311a, 311b, 311c, 311d, 311e and 311f. As each of these switches opens, the coil of the associated relay will be de-energized, so that the relays will return to inoperative position. When the coils of relays 452, 453, 454, 455, 456 and 457 are de-energized and relay 434 is energized a circuit will be completed from wire 396 through wire 487, switch 475, wire 488, switch 472, wire 489, switch 468, wire 490, switch 465, wire 491, switch 462, wire 492, switch 459, wire 493, switch 483, wire 494, and motor 58 to wire 397. When switch 168 is operated by cam 167 touching the switch lever, switch 168 will momentarily connect wire 396 with wire 495 and will break the circuit between wires 396 and 485. This will complete a circuit from wire 396 through switch 168, wire 495 and the coil of relay 496 (Figure 32C) to wire 397. This will cause relay 496 to operate and close switches 497 and 498. When switch 497 is closed it will complete a circuit from wire 396 through switch 497 and drive motor 178 (Figures 8 and 32C). Switch 182 (Figures 24 and 32C) will normally connect wire 396 to wire 499. When switch 498 is closed, a holding circuit will be completed from

wire 396 through switch 182, wire 499, switch 498, wire 500 and the coil of relay 496 to wire 397. When cam 181 (Figure 24) contacts the switch lever of switch 182, the switch will momentarily connect wire 396 to wire 501. This will complete a circuit through the coil of relay 502 to wire 397. When relay 502 is energized it will close switches 503 and 504. Closing switch 503 will complete a circuit from wire 396 through switch 503 and motor 315 (Figures 26 and 32C) to wire 397. 10 Switch 343 (Figures 25 and 32C) is normally closed, and when relay 502 is energized, a holding circuit will be completed from wire 396 through switch 343, switch 504, wire 505 and the coil of relay 502 to wire 397. Switch 346 (Figures 25 and 32C) is normally open. When the switch is operated by cam 344 coming in contact with switch lever 345; switch 346 will momentarily close and complete a circuit from wire 396 through the coil of relay 506 to wire 397. Operation of relay 506 will close switches 507 and 508. When switch 507 is closed it will 20 complete a circuit from wire 396 through a motor 509 which drives the arms 376 (Figure 1B) in the painter. 14. When motor 509 is energized, it will draw arms 376 into the painter. When they have been drawn in their full distance, the motor will return them to the extended position. Switch 510 which is concealed within the painter is normally closed. When relay 506 is energized a holding circuit will be completed from wire 396 through switch 510, switch 508, wire 511 and the coil of relay 506 to wire 397. When the arms have made a complete 25 cycle and been returned to the extended position, a cam attached to the drive means will momentarily open switch 510 (Figure 32C), breaking the holding circuit. It will be obvious to anyone skilled in the art that additional devices such as indicating lights, safety switches 35 and manual switches to override the automatic control system may readily be incorporated in the system without changing its normal function.

Operation

40. The continuous lath line as readied for operation by placing a coil of strip 2 (Figure 1A) on the payoff reel 1 and feeding it into the rotary slitter 4. Spools of wire for fastening the sheets into bundles are placed upon their reels and fed from the reels through conduits 379 (Figure 9) to hollow sleeve 277 (Figure 17) and the grooved fastening wire feed roll and the flat fastening wire feed roll in the fastening units. Pressing the tip of lever 264 (Figure 18) will move flat fastening wire feed roll 262 away from grooved fastening wire feed roll 257 and allow the wire to be threaded between the rolls through hollow sleeve 278 (Figure 17), hole 279 in spindle 274 and tubular member 280 to the shear knives 232 and 234. The fastening wire will be firmly grasped in groove 258 in grooved fastening wire feed roll 257. The continuous lath line is now ready to run.

45. Closing switch 383 (Figure 32A) will connect wires 384 and 385 to the line. Depressing push button 386 will energize relay 389 and close switches 391, 392 and 393. This will connect wires 396 and 397 to the line. 50. After push button 386 is released, relay 389 will remain operative by virtue of the holding circuit through switches 394 and 391. The rotary slitter is supplied with coolant by a pump (not shown in the drawings). When this pump has been started and is supplying coolant under full pressure, pressure switch 398 will close. Since fastening wire has been fed into all of the conduits 379, switches 380a, 380b, 380c, 380d, 380e and 380f will be closed. Thus, when switch 398 closes, relay 399 will be energized closing switches 400 and 401. When switch 401 is closed the operator will be able to start the main drive motor from motor controller 402. Should switch 401 be open, the main drive motor would not start. When the main drive motor is started, a brake on the motor will be released closing switch 403. Consequently, 55. when the main drive motor is started a circuit will be

completed through the motor 25 of the speed-up belt starting the belt.

The strip which has been started into the line will be cut in the rotary slitter 4, expanded in the expander 5 and leveled in the roller leveler 6. Guide 8 will lead it to the pinch rolls 9 from which it will be fed to flying shear 10. Until the leading edge of the strip has been fed into the pinch rolls it may be desirable to operate the main drive motor at a reduced rate of speed so that the strip may be led into the various units properly. Once the strip has been fed into the pinch rolls the operation will be continuous from the payoff reel to the flying shear and the speed of the operation may be increased.

As the strip of expanded metal passes through the flying shear the leading edge will be lying on speed-up belt 11a. When a length of strip equal to the length of the finished sheets has passed through the flying shear, it will cut a sheet from the end of the advancing strip. Now, being released from the strip, the sheet will be carried rapidly into the bundler by the speed-up conveyor 11.

The pinch rolls 9 are normally closed only in starting and finishing a coil of strip.

Each sheet will be delivered between guides 33 (Figure 5) and onto angles 34a and 35a. The inertia of the sheet will carry it until its leading edge comes to a halt against the resilient stop 36 (Figure 6). As each sheet passes beneath switch 53 it will strike roller 55 on the end of the switch lever and close the switch. This will energize timer 404 (Figure 32A). After a predetermined lapse of time sufficient to allow the sheet to settle in predetermined position on the angles against the resilient stop, timer 404 will energize timer 405. Timer 405 will operate relay 406 for a sufficient length of time to operate valve 410 causing arms 34 and 35 to open and drop the sheet of lath held by them to the supports beneath. Timer 405 will at the same time energize timer 407. After a predetermined lapse of time sufficient to allow the sheet to drop from between angles 34a and 35a, timer 407 will operate relay 415 for a sufficient length of time to operate valve 410 causing arms 34 and 35 to close. These will then be closed in time to receive the next sheet of expanded lath delivered by the speed-up conveyor. Operation of relay 415 will simultaneously close switch 417, operating the counter and counting one sheet.

When the supports in the bundler are in the position shown by the drawings and arms 34 and 35 open, they will allow the sheet which they hold to fall onto supports 94, 95, 96, 105, 106 and 107. These comprise a piling station upon which successive sheets delivered to the bundler and released from arms 34 and 35 are piled. Ten successive sheets will be disposed one on top of another in the manner hereinabove described. At this point cams 63, 64, 65, 66, 67, 68, 69, 70, 71, 72 and 73 are in the position shown in the drawings. When the tenth sheet is dropped from the arms 34 and 35 to the piling station, counter 421 (Figure 32B) will momentarily close switch 422. This will operate relay 423 closing switch 424. When switch 424 closes it will complete a circuit from wire 396 through the coil of relay 425 and switch 424 to wire 397. Operation of relay 425 will close switch 427 and complete a holding circuit through the coil of relay 425, wire 431, switch 427, wire 432, switch 433, wire 435 and switch 169 to wire 397. Operation of relay 425 will likewise close switch 426 completing a circuit through wires 428, 429 and motor 58. At the time the counter closes switch 422, it will also reset itself and count another ten sheets into the bundler before causing arms 34 and 35 to open again.

Closing the circuit through motor 58 will cause it to drive camshaft 62 (Figure 7) and all of the cams mounted upon it. Viewing Figures 10, 11, 13 and 15 the camshaft will rotate in a clockwise direction. Cams 66 (Figure 10) and 71 will immediately cause supports 94, 95, 96, 105, 106 and 107 to move to a lower position

comprising a fastening station. The supports will now be at the bundling station. As soon as supports 95, 96, 106 and 107 have been lowered enough to give sufficient clearance, cams 64 (Figure 11) and 69 will cause supports 97, 98, 99, 108, 109 and 110 (which are already at their highest elevation) to move inwardly into a position to support the next series of sheets dropped from arms 34 and 35. A new pile will then be formed on supports 97, 98, 99, 108, 109 and 110. When camshaft 62 has rotated 90° cam 63 (Figure 13) and cam 73 will have caused the six fastening units 185 to move inwardly toward the center line of the bundler. The shelf of the fastening end of each unit will be beneath the edge of the bundle with the spindle 274 below. Meanwhile, rotation of camshaft 62 will have caused the high point of cam 68 (Figure 15) to come next to roller 130. This will raise frame 138 until supports 141 are projecting above conveyor chains 142. Supports 141 will now co-operate with supports 94, 95, 96, 105, 106 and 107 in supporting the pile of sheets of expanded lath. At this point, after camshaft 62 has rotated 90°, cam 167 (Figure 4A) will strike the lever of switch 169 (Figures 4A and 32B) and will momentarily complete a circuit between wire 436 and wire 397. This will at the same time break the circuit between wire 435 and wire 397. Since this constitutes a part of the holding circuit for relay 425, relay 425 will be de-energized and switches 426 and 427 will open. When switch 426 opens, motor 58 and camshaft 62 will stop.

When switch 169 is operated by cam 167 it will energize the coil of relay 437 closing switch 438. This will complete a circuit through timer 439 activating the timer. Timer 439 will then energize the coil of relay 442 and hold it energized for a predetermined length of time. Operation of relay 442 will close switch 444 causing operation of relay 445. Operation of relay 445 will close switches 446, 447, 448, 449, 450 and 451. As each of these switches is closed it will complete a circuit through the coil of the associated relay causing it to operate. Operation of the relays will close switches 460, 463, 466, 469, 473 and 476 causing motors 190a, 190b, 190c, 190d, 190e and 190f to operate.

When relays 455 and 457 operate they will close switches 470 and 477, energizing relay 434. This will close switches 483 and 484 and open switch 433. Relay 434 will then be held closed by a holding circuit through switches 488 and 484.

As each of the motors operates it will rotate the input shaft 192 (Figure 17) of each of the fastening unit. This will rotate pinion 199 (Figure 20). Rotation of pinion 199 will cause planet gears 214, 215 and 216 to walk around internal gear 212, so that shafts 209, 210 and 211 will be moving in a circle about pinion 199. Simultaneously, planet gears 214, 215 and 216 will rotate about the axes of the shafts on the bushings which are mounted on inner bushings. Planet gears 223, 224 and 225 will have the same speed of rotation about the axis of shafts 209, 210 and 211 as planet gears 214, 215 and 216 since they are likewise keyed to the bushings.

The tangential velocity of planet gear 214 at its pitch line contact with the pitch line of internal gear 212 is zero relative to the fastening unit, since internal gear 212 is fixed to the fastening unit. This zero velocity will be made up of two components. One component will be the tangential velocity due to rotation of the planet gears 214, 215 and 216, shafts 209, 210 and 211 and spider 208 about the axis of pinion 199. The other component, of equal but opposite magnitude, will be the tangential velocity due to rotation of planet gear 214 about the axis of shaft 209. Because internal gear 212 is fixed, it is obvious that the magnitudes of these velocities must be equal but opposite. Since planet gears 215 and 216 are symmetrical with planet gear 214, they are subject to the same analysis.

Planet gear 223 is fixed to and moves with planet

gear 214. It is, however, of slightly smaller diameter. Likewise, the pitch diameter of internal gear 218 will be smaller than the pitch diameter of internal gear 212. Like planet gear 214, the tangential velocity of planet gear 223 at its pitch line contact with internal gear 218 will be made up of two components. One component will be the tangential velocity due to rotation of planet gears, 223, 224 and 225, shafts 209, 210 and 211 and spider 207 about the axis of pinion 222—which axis coincides with the axis of pinion 199. The angular velocity about the axis of pinion 222 will be the same as for the corresponding point on planet gear 214. Since, however, the pitch diameter of internal gear 218 is less than that of internal gear 212, the tangential velocity of planet gear 223 at its point of pitch line contact with internal gear 218 will be less than that of the corresponding point on planet gear 214. This component of tangential velocity in planet gear 223 will be less than that of the corresponding point on planet gear 214 by the ratio of the pitch diameter of internal gear 218 to the pitch diameter of internal gear 212. Differently stated, the ratio will be the pitch line radius of internal gear 212 reduced by the difference in pitch line radii of planet gears 214 and 223 to the pitch line radius of internal gear 212. The other component will be the tangential velocity due to rotation of planet gear 223 about the axis of shaft 209. Being fixed to planet gear 214, planet gear 223 will have the same angular rotation. The component of tangential velocity of planet gear 223 at its pitch line contact with internal gear 218 will be less than that of the corresponding point on planet gear 214 by the ratio of the pitch line radius of planet gear 223 to the pitch line radius of planet gear 214. Since planet gears 224 and 225 are symmetrical to planet gear 223, the same analysis will apply to them. The gear sizes are such that the reduction in tangential velocity due to rotation about the axis of shaft 209 is greater than the reduction in tangential velocity due to rotation about the axis of pinion 222.

Consequently, the resultant tangential velocity of planet gear 223 at its pitch line contact point with internal gear 218 will not be zero. The resultant velocity will be in the same direction of rotation as pinion 199.

The tangential velocity of planet gear 214 at its point of pitch line contact with pinion 199 is in the same manner composed of two components—one due to the rotation of planet gears 214, 215 and 216, shafts 209, 210 and 211 and spider 208 about the axis of pinion 199 and the other due to rotation of planet gear 214 about the axis of shaft 209. The summation of these two components will equal the tangential velocity of pinion 199 at its point of pitch line contact with planet gear 214. The same considerations will be true for planet gears 215 and 216 which are symmetrical with planet gear 214. As before described, planet gear 223 will be rotating about shaft 209. The entire assembly of planets gears 223, 224 and 225, shafts 209, 210 and 211 and spider 207 will be revolving about the axis of pinion 222 with the corresponding parts in Figure 20. The tangential velocity of pinion 222 will be the same as the tangential velocity of planet gear 223 at its point of pitch line contact with pinion 222. The component which is due to rotation about the axis of pinion 222 will be slightly larger than that for the corresponding point on planet gear 214 since pinion 222 is of greater diameter than pinion 199. The component due to rotation about the axis of shaft 209 will be smaller than that for the corresponding point on planet gear 214. The resultant velocity will be less than that of the corresponding point on planet 214 and pinion 222 will rotate in the same direction as, but at a slower speed than, pinion 199. Using a drive as here described with a drive motor running at 1800 revolutions per minute, I drive pinion 222 at 1100 revolutions per minute and internal gear 218 at 15.6 revolutions per minute.

Operation of the motor will first cause rotation of camshaft 202 (Figure 17) and member 245, causing the high part of cam 304 to come next to roller 305 and move clamp 297 into clamping position. Clamp 297 will then engage the edge of the bundle of sheets of expanded lath and compress them into a compact pile as shown in Figure 16. At the same time the tracks in which rollers 229 and 230 are fitted will converge, moving the shear knives 232 and 234 apart. The track in which roller 295 is fitted will cause the roller to move carriage 285 toward the bundle of lath so that the two arms of yoke 289 are positioned, one above the bundle and one below the bundle. Throughout this time spindle 274 is being rotated by compound gear 242, spindle 15 drive shaft 221 and pinion 222.

When camshaft 202 begins rotation, cam 304 will cause clamp 297 to clamp the edge of the bundle. Simultaneously, the track in which roller 294 is fitted will begin to move yoke 289 to a position to fit over the edge of the bundle; and the tracks in which rollers 229 and 230 are fitted will begin to open the shear knives. At about the time clamp 297 reaches its clamping position and while yoke 289 and shear knives 232 and 234 are still moving, the intermittent teeth (Figure 23) cut on portion 245a of member 245 will come into engagement with intermittent pinion 250. Pinion 250 will make one revolution in the time that the teeth are engaged. Thus, pinion 250 will make one revolution during each revolution of member 245. In the first half revolution of pinion 250 spindle 274 will be raised to its greatest height by spider 267. As the spindle moves upwardly with tubular member 280, the offset point 281 of tubular member 280 will hunt its way through the wire lath. As it moves upwardly through the lath the rotating point, which will describe a helical path, will find a hole in each sheet of lath and deform it slightly, if necessary, to create a hole straight through the bundle. Meanwhile the two fastening wire feed rolls 257 and 262 will be feeding wire upwardly through the tubular member 280. 20 When the upward motion is first started, the end of the wire will be projecting beyond the point 281 of tubular member 280 to the shearing surfaces of shear knives 232 and 234. The upward velocity of spindle 274 through most of its upward travel is higher than that of the wire, so that the point 281 will be ahead of the end of the wire when point 281 reaches the bundle of expanded lath. When the tubular member 280 has reached its uppermost point above the bundle and begins to withdraw, the end of the wire inside tubular member 280 25 will again reach above the point 281. The front end of the wire will reach above the bundle before the point of tubular member 280 is withdrawn into the bundle. As spindle 274 continues to be withdrawn wire will be fed upwardly through the hole in the lath formed by tubular member 280 until intermittent pinion 250 will have made a complete revolution and the flat portion of the pinion will again be next to member 245. Internal gear 218, spider 207, camshaft 202, member 245 and cam 292 will continue to rotate. The tracks in which 30 rollers 229 and 230 are fitted will diverge causing shear knives 232 and 234 to cut the fastening wire above them from that which is fed up through spindle 274. The cut portion of the fastening wire will be projecting through the holes 290 in yoke 289 and the sheets of lath.

Cam 292 will then cause carriage 285 to be withdrawn until yoke 289 is clear of the edge of the bundle of expanded lath. The ends of the wire will still be retained in holes 290. At this point the teeth on portion 245a of member 245 will engage intermittent pinion 283. Further rotation of member 245 will drive gear member 282a through one revolution. The ratio between pinion 284 and elongated pinion 291 is 2:1, so 35 that yoke 289 will make two complete revolutions. The

ends of fastening wire which will still be caught in holes 290 will be given two complete twists together.

This operation takes place in three locations on each side of the bundle so that the bundle is now wired together by six separate wires. Further rotation of member 245 will bring the low point of cam 304 next to roller 305. Springs 299 and 300 will return clamp 297 to the open position. Rod 308 will push operating pin 310 of switch 311 and open the switch on that fastening unit.

When each of the switches 311a, 311b, 311c, 311d, 311e and 311f (Figure 32B) are opened, the holding circuits to relays 452, 453, 454, 455, 456 and 457, respectively, will be broken. As this happens to each relay it will be de-energized and will return to inoperative position. As each relay is de-energized, the circuit to the associated motor will be broken, and in each case the motor will stop running. When either relay 455 or 457 is de-energized, the circuit from wire 396 through wire 480, switch 477, wire 481, switch 470, wire 482 and the coil of relay 434 to wire 397 will be broken. Relay 434 will remain operative, however, because of the holding circuit through switches 168 and 484. When all of the relays 452, 453, 454, 455, 456 and 457 have been de-energized, a circuit will be completed from wire 396 through wire 487, switch 475, wire 488, switch 472, wire 489, switch 468, wire 490, switch 465, wire 491, switch 462, wire 492, switch 459, wire 493, switch 483 and wire 494 through motor 58 to wire 397. The result is that as each fastening unit reaches the end of its cycle its particular motor will be stopped. When all of the fastening units have reached the ends of their cycles, motor 58 will be connected and will again start to drive cam-shaft 62.

As cam-shaft 62 starts to rotate again, the low portion 127 (Figure 10) of cam 66 and corresponding portion of cam 71 will come next to the respective cam follower rollers. This will cause supports 94, 95, 96, 105, 106 and 107 to drop further, and the tied bundle of lath will be left supported on supports 141. Cam 67 (Figure 11) and cam 72 will then cause rotation of splined shafts 90, 91, 92 and the shafts associated with supports 105, 106 and 107. This will rotate supports 94, 95, 96, 105, 106 and 107 to the outward or inoperative position. At the same time, rotation of cams 63 (Figure 13) and 73 will cause the fastening units to be withdrawn from the edge of the bundle.

Further rotation of cam-shaft 62 will cause a low portion of cam 68 (Figure 15) to again come next to roller 130 dropping frame 138 and supports 141 below conveyor chains 142. This will leave the bundle of lath resting on the conveyor chains just in front of the dog 177 as shown in Figure 15. At the same time the high point of cam 66 will again come next to roller 113 (Figure 10) and similar action will take place with respect to cam 71. This will elevate supports 94, 95, 96, 105, 106 and 107 up to the same elevation as supports 97, 98, 99, 108, 109 and 110 on which sheets delivered to the bundler are now being piled. When cam-shaft 62 has rotated through 90° after the fastening operation, or 180° from its original position as shown in the drawings, cam 167 will touch the lever of switch 168 (Figures 4A and 32B) and cause it momentarily to break the contact between wires 396 and 485 and momentarily to make contact between wires 396 and 495.

When ten more sheets have been delivered to the bundler, the same process will take place again. Cam-shaft 62 will again rotate through 180°. This time, however, the pile of sheets will be carried upon supports 97, 98, 99, 108, 109 and 110. As they move downwardly with a pile of sheets to the bundling station, supports 94, 95, 96, 105, 106 and 107 will again move into operative position to support sheets dropped from arms 34 and 35.

When the circuit is broken between wires 485 and 396,

the holding circuit for relay 434 through wires 485, switch 484, wire 486 will be broken. This will cause switch 483 to open breaking the circuit to motor 58 and stopping it. Operation of the switch will momentarily make a circuit from wire 396 through wire 495 and the coil of relay 496 (Figure 32C) to wire 397, closing switches 497 and 498. Switch 182, wire 499, switch 498 and wire 500 constitute a holding circuit through the coil of relay 496 to wire 397. Closing switch 497 will complete a circuit from wire 396 through conveyor drive motor 178 (Figures 8 and 32C). When switch 168 is operated, relay 496 will become operative and will remain so until switch 182 disconnects wire 499 from wire 396.

Operation of motor 178 will cause the conveyor chains 142 to move the bundle on them toward the turntable. Dogs 177 (Figure 4B) will push the bundle ahead and prevent slippage. When the dogs have gone the full length of the bundler to the position shown in Figure 4B, cam 181 (Figure 24) will operate switch 182. Operation of switch 182 (Figures 24 and 32C) will break the circuit from wire 396 to wire 499. This being a part of the holding circuit for relay 496, the relay will be de-energized and switches 497 and 498 will open. Opening of switch 497 will disconnect motor 178 from the line and bring it to a stop. At the same time switch 182 will momentarily connect wire 396 and wire 501 energizing relay 502. Operation of relay 502 will close switches 503 and 504 completing a holding circuit for the relay from wire 396 through switches 343, 504 and wire 505 to wire 397. Closing switch 503 will complete a circuit through turntable motor 315 starting operation of the turntable.

When the motor is energized it will drive pinion shaft 319 (Figure 28) causing rotation of cams 330 and 336. Cam 336 will first partially elevate the turntable so that the end of the bundle thereon will be clear of the chain conveyor and dogs. Cam 330 will then cause rotation of the turntable through 90° so that the bundle will be sideways to the turntable. Cam 336 will then raise the turntable to full elevation raising turntable surface 364, above the level of guides 371. At this point cam 336 will have rotated 180° from the position shown in Figure 28.

At this point cam 344 (Figure 25) will contact switch lever 345 of switch 346 (Figures 25 and 32C) this will momentarily close switch 346 connecting the coil of relay 506 across the line. This will close switches 507 and 508 completing a holding circuit for relay 506 through switches 510 and 508. Closing switch 507 will operate motor 509 drawing the bundle sideways into the painter where it will be processed in the normal manner. The bundle will be drawn off the turntable and into the painter before the fully elevated portion 362 of cam 336 has passed beyond roller 349. When cam 336 has made a full revolution it will allow the turntable to return to its lower position. At this time cam 341 (Figure 25) will contact switch lever of switch 343 (Figure 32C) momentarily opening the switch. This will break the holding circuit for relay 502 causing switches 503 and 504 to open and breaking the circuit to the turntable motor 315. When motor 509 has driven arms 376 through a complete cycle, a cam on the driving means will momentarily open switch 510. This will break the holding circuit for relay 506 causing switches 507 and 508 to open and motor 509 to stop.

When sheets of expanded lath are stacked, their configuration causes each successive sheet to be displaced slightly from the one below it. The result is that when a pile of sheets is stacked regularly it tends to have its sides at an angle instead of vertical. When the pile is deep, this can make handling very unwieldy. This problem is avoided by stacking successive bundles with their set or configuration in opposite directions. Then when the bundles are stacked coming out of the painter the

set which they have due to configuration of the lath will be in alternate directions for each successive bundle. This will maintain a pile of bundles as a relatively vertical pile instead of slanting off in one direction.

When the turntable completes its cycle, it will be returned to its low elevation to receive a new bundle from the bundler. It will, however, be rotated 90° from its earlier position. When the next bundle is delivered to the turntable it will be rotated 90° in the opposite direction from that of the preceding bundle. Thus, successive bundles will have their opposite edges delivered first into the painter, and the bundles delivered from the painter may be directly piled without further turning to avoid piles which are not vertical.

It will be seen that strip is fed continuously into the continuous lath line. It is automatically cut to length, piled and counted, fastened into bundles and delivered to the painter without any labor beyond that of supervision.

When it is desired to shut the continuous lath line down after operation the main drive motor controller 402 (Figure 32A) may be used to stop the main drive motor. This will stop operation of the rotary slitter, the expander, the roller leveler, pinch rolls and flying shear. The line may be slowed down before stopping until exactly ten sheets have been delivered to the bundler. The bundler will continue to operate automatically and will deliver the last bundle to the turntable and painter. At this point push button 394 can be used to break the holding circuit for relay 389. This will open switches 391, 392 and 393 and disconnect the control system from the line.

The apparatus is claimed in my divisional applications Serial No. 648,699, filed March 26, 1957, and Serial No. 725,405, filed March 31, 1958. Application Serial No. 648,699 has been abandoned in favor of copending continuation application Serial No. 798,088, filed March 9, 1959.

While I have illustrated a present preferred method of practicing the invention and a modification thereof, it is to be distinctly understood that the invention is not limited thereto but may be otherwise variously practiced within the scope of the following claims.

I claim:

1. A method of making, bundling and treating expanded lath comprising advancing a blank, during the advance of the blank slitting and expanding the blank to form expanded lath and shearing the lath into sheets, continuing the advance of the sheets one after another to a receiving station, during such continued advance speeding up to the sheets to form spaces therebetween, forming the sheets into a pile, fastening the sheets of the pile together to form a bundle, applying coating material to the bundle and drying the bundle.

2. A method of handling sheets of expanded lath or the like comprising successively delivering a first group of sheets of expanded lath or the like onto a pile with the strands of all of the sheets inclined in the same direction, fastening the piled sheets together to form a first bundle, moving the first bundle to a stacking station, depositing the first bundle at the stacking station with the strands inclined in a predetermined direction, successively delivering a second group of sheets of expanded lath or the like onto a pile with the strands of all of the sheets inclined in the same direction, fastening the piled sheets together to form a second bundle, moving the second bundle to the stacking station and depositing the second bundle atop the first bundle with the strands of the second bundle inclined in the direction opposite said predetermined direction.

3. A method of handling sheets of expanded lath or the like comprising successively delivering a first group of sheets of expanded lath or the like onto a pile with the strands of all of the sheets inclined in the same direction, fastening the piled sheets together to form a first bundle,

turning the first bundle through approximately 90° in one direction and depositing it at a stacking station, successively delivering a second group of sheets of expanded lath or the like onto a pile with the strands of all of the sheets inclined in the above mentioned direction, fastening the piled sheets together to form a second bundle, turning the second bundle through approximately 90° in the direction opposite the direction of turning of the first bundle and depositing the second bundle atop the first bundle at the stacking station.

4. A method of making and piling sheets of expanded lath comprising advancing a blank of lath material, during the advance of the blank slitting and expanding the blank to form expanded lath, shearing the advancing lath into sheets and delivering the advancing sheets in the same general direction as the direction of advance of the blank but at a speed greater than the speed of the advancing lath prior to hearing to provide spaces between the advancing sheets so that the advance of the material is continuous before, during and after shearing, and continuing the advance of the spaced apart sheets one after another to a receiving station where the sheets are stopped in predetermined position, and forming the sheets into a pile.

5. A method of making and piling sheets of expanded lath comprising advancing in a generally horizontal plane a blank of lath material, during the advance of the blank slitting the blank and expanding it generally into a plane at an angle to the horizontal to form expanded lath, turning the advancing lath into a generally horizontal plane, shearing the advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing and also during turning of the lath into a generally horizontal plane, and continuing the advance of the spaced apart sheets one after another to a receiving station where the sheets are stopped in predetermined position, and forming the sheets into a pile.

6. The method of making and piling sheets of expanded lath comprising advancing in a generally horizontal plane a blank of lath material, during the advance of the blank slitting the blank and expanding it generally into a plane at an angle to the horizontal to form expanded lath, turning the advancing lath into a generally horizontal plane, during advance of the lath in said generally horizontal plane shearing the advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing and also during turning of the lath into a generally horizontal plane, and continuing the advance of spaced apart sheets one after another to a receiving station where the sheets are stopped in predetermined position, and forming the sheets into a pile.

7. A method of making and piling sheets of expanded lath comprising advancing a blank of lath material in a generally horizontal direction generally in a plane at an angle to the horizontal, during the advance of the blank in such plane slitting the blank, during the continued advance of the slit blank expanding the slit blank into a generally horizontal plane to form expanded lath, continuing the advance of the lath in such plane, during such continued advance of the lath shearing the lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing,

and continuing the advance of the spaced apart sheets one after another to a receiving station where the sheets are stopped in predetermined position, and forming the sheets into a pile.

8. A method of making and piling sheets of expanded lath comprising advancing a blank of lath material, during the advance of the blank slitting and expanding the blank to form expanded lath, shearing the advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing, continuing the advance of the spaced apart sheets one after another to a receiving station where the sheets are stopped in predetermined position, moving the sheets one after another from the receiving station to a piling station and forming the sheets into a pile at the piling station until there are a predetermined number of sheets in the pile and then lowering that pile downwardly from the piling station and similarly forming a new pile.

9. A method of making and bundling sheets of expanded lath comprising advancing a blank of lath material, during the advance of the blank slitting and expanding the blank to form expanded lath, shearing the advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing, continuing the advance of the spaced apart sheets one after another to a receiving station where the sheets are stopped in predetermined position, forming the sheets into a pile and fastening the sheets of the pile together to form a bundle.

10. A method of making and bundling sheets of expanded lath comprising advancing a blank of lath material, during the advance of the blank slitting and expanding the blank to form expanded lath, shearing the advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing, continuing the advance of the spaced apart sheets one after another to a receiving station where the sheets are stopped in predetermined position, moving the sheets one after another from the receiving station to a piling station and forming the sheets into a pile at the piling station, shifting the pile to a bundling station and at the bundling station applying fastening means to the sheets of the pile to fasten the same together to form a bundle.

11. A method of making and bundling sheets of expanded lath comprising advancing a blank of lath material, during the advance of the blank slitting and expanding the blank to form expanded lath, shearing the advancing lath into sheets and delivering the advancing sheets in the same general direction as the direction of advance of the blank but at a speed greater than the

65

speed of the advancing lath prior to shearing to provide spaces between the advancing sheets so that the advance of the material is continuous before, during and after shearing, continuing the advance of the spaced apart

5 sheet one after another to a receiving station where the sheets are stopped in predetermined position, forming the sheets into a pile, shifting the pile to a bundling station, at the bundling station applying fastening means to the sheets of the pile to fasten the same together to 10 form a bundle and simultaneously with the application of the fastening means to the sheets of the aforementioned pile similarly forming another pile.

12. A method of making and bundling sheets of expanded lath comprising advancing a blank of lath material, during the advance of the blank slitting and expanding the blank to form expanded lath, shearing and advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing, continuing the advance of the spaced apart sheets one after another to a receiving station where 20 the sheets are stopped in predetermined position, forming the sheets into a pile, fastening the sheets of the pile together to form a bundle and delivering the bundle generally in the same direction as the direction of advance of the sheets to the receiving station.

13. A method of making and piling sheets of expanded lath comprising advancing a blank of lath material, during the advance of the blank slitting and expanding the blank to form expanded lath, shearing the advancing lath into sheets and delivering the advancing sheets in the same general direction as the direction of advance of the blank but at a speed greater than the speed of the advancing lath prior to shearing to provide spaces between the advancing sheets so that the advance of the material is continuous before, during and after shearing, continuing the advance of the spaced apart sheets one after another to a receiving station where the sheets are stopped in predetermined position, moving the sheets one after another from the receiving station to a piling station and forming the sheets into a pile at the piling station until there are a predetermined number of sheets in the pile.

14. A method of making and piling sheets of expanded lath comprising advancing a blank of lath material, during the advance of the blank slitting and expanding the blank to form expanded lath, shearing the advancing lath into sheets and delivering the advancing sheets in the same general direction as the direction of the blank but at a speed greater than the speed of the advancing lath prior to shearing to provide spaces between the advancing sheets so that the advance of the material is continuous before, during and after shearing, continuing the advance of the spaced apart sheets one after another to a receiving station where the sheets are stopped in predetermined position, lowering the sheets one after another from the receiving station to a piling station and forming the sheets into a pile at the piling station.
